Attorneys.

UNITED STATES PATENT OFFICE.

GEORGE X. WENDLING, OF SAN FRANCISCO, CALIFORNIA.

COMPARTMENT END CLOSURE FOR BOXES.

Application filed February 13, 1922. Serial No. 536,918.

To all whom it may concern:

Be it known that I, GEORGE X. WENDLING, a citizen of the United States, residing at the city and county of San Francisco and 5 State of California, have invented certain new and useful Improvements in Compartment End Closures for Boxes, of which the following is a specification.

Shipping boxes or receptacles particularly 10 that type of box employed for packing and transporting citrus fruits as at present universally constructed consists of end members or compartment division members cut from a single board, and to the edges of the end 15 members are nailed the box side, top and bottom walls. The nails holding certain opposing walls in position firmly engage the end members as they are driven thereinto across the grain while the nails holding the 20 other walls are easily extracted, due to their being driven into the ends longitudinally of the grain.

The end members as at present used are quite thick to afford strength and are consequently heavy, the thickness affording a 25 transverse area for driving nails endwise of the grain.

My present invention relates to an improvement in box or compartment ends particularly designed to be utilized in the construction of boxes for shipping citrus fruits, and by which invention there is presented a cross grain at the periphery of the end member and into which the securing means, 35 such as the nails for the walls, are driven, insuring maximum strength for the package and overcoming the liability of the securing means becoming loose in the shipment of the receptacle.

40 The invention further relates to a panel type of box end wherein a frame forms the periphery of the end and is closed in its center by a closing panel of a thickness less than that of the frame, and one wherein the 45 inner peripheral edge of the frame at opposite sides of the panel is cut or formed to present a smooth surface to the contents of the receptacle.

The present invention is designed for construction from material now discarded and destroyed by the lumber mills and the box factories generally, enabling a conserving of the lumber by utilization of the waste material, which materially reduces the cost of 55 manufacture of the end below that where new or special material would be required.

With the above mentioned and other objects in view, the invention consists in the novel construction and combination of parts hereinafter described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

To more clearly comprehend the invention, reference is directed to the accompanying drawings, wherein—

Fig. 1 is a view in perspective of the preferred embodiment of my invention.

Fig. 2 is a vertical sectional view taken on line 2—2 of Fig. 1.

Fig. 3 is a view in detail section of one of the corners illustrating the securing means for the frame forming members.

Referring more particularly to the drawings, wherein like characters of reference 50 designate corresponding parts—1 indicates a rectangular frame formed of interconnected wood members 2 disposed with the inner edges of adjacent members at right angles to each other. Certain of the members 2 are formed at their opposite ends with tenons 3, each of which is received within a mortise 4 formed in the end of a co-operating member 2. This construction provides a rigid joint connection between cooperating members 2 as the material or top of the members 2 provided with tenons lies in contact, as at 5, with that portion of the co-operating members 2 formed with mortises for the full depth of the mortise joint. The 55 interlocked ends of the members 2 are united by staples or other securing means 6 which pass therethrough transversely of the grain.

It will be observed from Fig. 1 that the frame forming members 2 are arranged with the grain extending longitudinally thereof, thereby affording a cross grain to a securing member driven into the periphery of the frame. The inner periphery of the frame between its opposite faces 7 and 8 is annularly grooved, as at 9, to receive a frame closing panel 10 of a thickness considerably less than that of the frame.

To present a relatively smooth surface to the contents of a box or receptacle constructed with one of the improved ends, I prefer to cut, fashion, or round the frame

edge at one or both sides of the panel 10, as at 11. When the panel is employed as a dividing panel between two compartments, as, for example, the center division member in a citrus fruit box, both of the inner peripheral edges of the frame are rounded as at 11 to present a smooth surface to the contents of the receptacle in each compartment, but where the member is used at one end of a compartment, it is only necessary to round or fashion one edge 11 thereof.

It will be observed that the frame members 2 are of comparatively short length, also the panel 10 is formed of relatively thin material, and the positioning thereof within the center of the frame adds strength to the frame and enables the same to be constructed considerably lighter than the solid box ends now universally in use.

20 It is to be understood that the panel closing the frame opening may be of veneer, card-board or any suitable material and the construction of the same is not confined to wood.

I claim:—

An end wall for a receptacle compartment comprising a rectangular frame consisting of side and end pieces having interlocking connection at their intersecting opposite ends, the grain in each extending longitudinally thereof, the inner surface of each side and end piece of said frame being centrally channelled, a single panel within the frame for closing the opening therein, with its peripheral edges received within said channel and disposed with its opposite faces spaced inwardly from the opposite faces of said frame, the outer opposite edges of the channels around each face of said panel being rounded to present a relatively smooth surface to the contents of a receptacle compartment, and means for permanently connecting co-operating side and end pieces to retain said panel within said frame with its edges received within said groove.

In testimony whereof I have signed my name to this specification.

GEORGE X. WENDLING.
